[57] CLAIM

The ornamental design for an electromagnetic display, as shown and described.

DESCRIPTION

FIG. 1 is a top plan view of an electromagnetic display showing my new design;

FIG. 2 is a left side view thereof;

FIG. 3 is a front elevational view thereof;

FIG. 4 is a right side view thereof;

FIG. 5 is a bottom plan thereof; and

FIG. 6 is a rear elevational view thereof;

The cords are fragmentarily shown in FIGS. 2, 4, 5 and 6 for convenience of illustration.
